EXAMINATION PAPER GRADING APPARATUS

Wesley S. Roeder, Portland, Oreg.

Application January 18, 1954, Serial No. 404,662

7 Claims. (Cl. 35—48)

This invention relates to apparatus for grading multiple choice examination papers by the method wherein use is made of a perforated or otherwise altered key sheet, the perforations or alterations on which indicate the location of the correct answers on the examination paper.

It is a primary object of the present invention to provide examination paper grading apparatus of the class described which is more efficient and more rapid than are the devices of the prior art which have been developed for analogous purposes.

It is another object of the present invention to provide an examination paper grading apparatus which grades the papers with a high degree of accuracy.

It is another object of the present invention to provide an examination paper grading apparatus which may be used on answer sheets having a large number of answers, for example, up to several hundred answers on each sheet.

It is another object of the present invention to provide an examination paper grading apparatus which may be used for the determination of sub-total scores as well as total scores.

It is another object of the present invention to provide an examination paper grading apparatus which is simple in construction and substantially free from vibration so as to be adaptable for use with electronic scanning and computing apparatus.

The manner in which the foregoing and other objects of this invention are accomplished will be apparent from the following specification and claims considered together with the drawings, wherein:

Figure 1 is a plan view of the presently described examination paper grading apparatus;

Figures 2, 3 and 4 are views in side elevation of the apparatus of Figure 1, illustrating the apparatus in loading, scanning, and discharge positions, respectively;

Figure 5 is a sectional view taken along the line 5—5 of Figure 4; and

Figure 6 is a plan view of an answer sheet of the type which may be scored by the presently described apparatus.

Upon reference to Figure 6 it will be observed that the answer sheet 10 contains a large number of areas 12 delineated by circles or other appropriate markings. These areas are arranged in groups, for example, groups 14, 16, 18, 20 and 22, each of which contains 5 rows, each row containing 30 answer spaces. The score given the examination as a whole will be the sum of the scores obtained on each of these groups.

When taking the examination, as is usual of examinations of this class, the student alters in some way the answer area which he believes to correspond to the correct answer. The alteration may be effectuated in any desired manner, as by punching out the area. Preferably, however, it is accomplished by coloring it with a pencil to give a darkened area having light reflective properties different from those of the surrounding sheet. The present invention is described with particular reference to this latter type of alteration of the answer sheet, although no limitation is intended thereby.

The answer sheet of Figure 6 may be graded by use of a key sheet 24 of corresponding form and proportions. The correct answers are indicated on the key sheet by alteration of certain ones 25 of the circled areas, preferably by punching them out. Also, the key

2

preferably is prepared on relatively stiff, heavy paper for permanency and ease of handling.

The apparatus employed for scoring answer sheets 10 includes a frame 30 of suitable construction and design.

5 It is dimensioned for reception of the answer sheets and is formed or provided with a pair of longitudinal tracks 32, 34.

A plurality of photoelectric cells 36 are arranged in the frame in five rows indicated at 38, 40, 42, 44 and 10 46 in Figure 4. Each of these rows contains 30 cells spaced apart laterally to correspond to the spacing of answer areas 12 on the answer sheet. Also, each row is positioned for scanning a corresponding one of answer groups 14—22.

15 The photoelectric cells are shielded by means of a light transmissive member such as the glass plate 48. They are energized by light from a suitable source, as by means of fluorescent lights 50, 52, 54, 56 and 58, one light being provided for each row of cells.

20 Slidably mounted upon tracks 32, 34 is a carriage 60. This serves the function of positioning the answer and key sheets and of holding the former securely superimposed upon the latter while they are scanned by the photoelectric cells.

25 The carriage is mounted for reciprocation between loading, scanning and discharge positions and is connected to suitable drive means for accomplishing this movement, as will be described more fully hereinafter.

Also, it is provided with a floor comprising the perforated bed plate 62. The perforations 64 in this plate are spaced apart to correspond to the spacing of photoelectric cells 36 and of the circled answer areas on answer sheet 10. Thus, they may be arranged in five groups, each group containing five rows of 30 openings each.

30 It is obviously of critical importance to the successful operation of the presently described apparatus that the key sheet and answer sheet be maintained in exact registration with each other and with the perforations 64 in the perforated plate 62 which forms the floor of the carriage. When this is the case, the openings punched out of the answer sheet will register exactly with the corresponding openings in plate 62 and with the answer areas on the answer sheet, which may or may not be shaded with pencil, depending upon whether or not the student has selected the correct answers.

35 In the illustrated form, the positioning means employed comprise a pair of longitudinally placed guides which may comprise the side walls 66, 68 of the carriage. These are spaced apart a distance such that they contain exactly the key and answer sheets, preventing their lateral displacement.

40 The longitudinal displacement of the key and answer sheets is prevented during operation of the apparatus by stop means stationed rearwardly of the carriage. Although various types of stops may be used for this purpose, a preferred form is illustrated particularly in Figure 1. It comprises a pair of spring pressed dogs 70, 72 pivotally mounted on opposite sides of the rear end of the carriage.

45 These dogs are formed with angular inner surfaces designed to engage the corners of the key and answer sheets. They also are formed with angled outer surfaces 74, 76 positioned for slidable engagement with frame members 78, 80 when the carriage is in its advanced position. Such engagement causes a lateral spreading of the dogs to the dotted line position of Figure 1, clearing the answer sheets for discharge from the apparatus.

50 The key and answer sheets are held securely in position during the scanning operation by hold-down means which may comprise a hold-down plate 82, the rearward end of which is notched as indicated at 84, 86. This member is adapted to be alternately raised for introduction of an answer sheet, lowered for holding the answer sheet down for scanning, and elevated again for discharge of the answer sheet.

55 Suitable drive means are provided for reciprocating the carriage and also for raising and lowering the hold-down member. In the embodiment shown in the drawings, these two drives are combined as follows:

60 Mounted on the frame of the apparatus is a motor,

not shown, which drives the gear box 90. The latter, in turn drives shafts 92, 94 on which are mounted worms 96, 98.

The latter elements drive worm gears 100, 102 which, in turn, drive wheels 104, 106 through shafts 103, 110. Members 100—106 carry crank pins, those on gears 100, 102 being indicated at 112, 114. The crank pins are connected to one end of the crankshafts 116—122. The intermediate portions of the crankshafts slidably engage guideways 124—127 in carriage 60. Their other ends are slidably mounted in extensions of hold-down member 82 and are provided with support pins 128—130 which support the hold-down members as the shafts are elevated. Accordingly, as members 100—106 rotate, carriage 60 will be reciprocated and hold-down member 82 will alternately be elevated and lowered.

Means are provided for discharging the answer sheets from the apparatus after they have been scored. Although various types of discharge means may be employed, a preferred form comprises two pairs of friction rollers 131—132 and 134—136. These may be mounted on shafts 138, 140 which in turn, may be supported between frame members 78, 80. One or both of the friction rollers may be power driven by drive means not illustrated. They function to grasp the answer sheet, operating through slots 84, 86 in hold-down member 82, and to discharge it into the receiving box 142.

As the carriage is reciprocated and the hold-down member alternately raised and lowered, the answer sheets are scanned by photoelectric cells 36 and the resulting electrical impulses employed to operate a computer 150 which is electrically connected to the photoelectric cells through cable 152. The computer may be of conventional construction and is provided with a control 154 which may be set to obtain the sub-total score or the total score as desired.

The computer in turn is connected electrically through cable 152 and the flexible connector 156 with a plurality of electrically operated printing mechanisms 158—168. These may be of any suitable construction and are mounted rigidly on hold-down member 82. They print the score on the answer sheet at the conclusion of the scanning operation while the hold-down member is still in contact with the sheet. Five of them, for example 158—166, may print the sub-total scores of answer groups 14—22. Another, 168 may print the total score.

Operation

In operation the key sheet 24 is placed on the perforated bed 62 of carriage 60 with the punched out openings 25, which correspond to the correct answers, in registration with openings 64 in the bed plate. The answer sheet 10 then is superimposed upon the key sheet with the circled areas 12 faced toward the latter. While thus positioned on the carriage, the answer and key sheets are aligned by means of guides 66, 68 and stop members 70, 72.

The student has previously shaded the circled areas which he thinks correspond to the right answers, and if his selection has been correct, a colored or shaded area will be behind each of the openings 25 in the key sheet. However, if his selection has been erroneous, blank areas of relatively high light reflective properties will be present behind these openings.

Operation of the mechanism then is instituted by manipulation of a suitable control 170. This moves the apparatus through one cycle only, i. e. from the position of Figure 2 through that of Figure 3, through that of Figure 4, and finally back to the starting position of Figure 2.

In the loading position of Figure 2, the hold-down plate 82 is elevated and dogs 70, 72 are in position. As the cycle starts and gears 100, 102 move in a clockwise direction as viewed in Figure 2, the carriage is retracted and the hold-down member is lowered until it contacts and holds down the answer and key sheets.

The scanning operation then begins (Figure 3). Light from sources 50—58 is transmitted through glass plate 48, through perforations 64 in bed plate 62, and through openings 25 in answer card 24. If pencilled areas lie behind these openings, a substantial amount of the light will be absorbed. However, if the areas behind these openings are blank, the light colored paper

will reflect the major proportion of the light. Accordingly there is produced a relatively strong, or relatively weak reflection of light which is picked up by photoelectric cells 36. These react accordingly and send impulses to the computer 150 which scores the answer sheet and transmits the scores either as sub-totals or total score, depending upon the setting of dial 154, to printing mechanisms 158—168.

Continued rotation of gears 100, 102 bring the carriage to the discharge position of Figure 4. In this position hold-down member 82 is slightly elevated by engagement with pins 128—130 on crank shafts 116—122. Also, dogs 70, 72 have been spread to the position indicated by the arrows of Figure 1 by contact of their angular surfaces 74, 76 with frame members 78, 80.

The two pairs of friction rolls 131—136 thereupon engage the answer sheet and withdraw it from the carriage, discharging it into receptacle 142. The cycle continues until the carriage and hold-down members have reassumed the starting position of Figure 1, when their motion is arrested pending another manipulation of control 170. It will be apparent that although in the above described apparatus the answer sheet has moved relative to the photoelectric cells, the construction could be modified so that the reverse is true and the photoelectric cells moved with respect to the answer sheet. Also, although it is preferred for reasons of accuracy to operate the apparatus one cycle at a time, suitable feeding apparatus may be coordinated with it so that the answer sheets are fed automatically and the scoring thereof takes place continuously.

Hence by the present invention I have provided examination grading apparatus which is rapid and highly accurate. It also is versatile being applicable to the grading of papers having a variable number of answers. Furthermore, the apparatus is adaptable for use in situations wherein it is desired to obtain sub-total scores as well as in those where the total score only is desired.

It is to be understood that the form of my invention, herewith shown and described, is to be taken as a preferred example of the same, and that various changes in the shape, size and arrangement of parts may be resorted to, without departing from the spirit of my invention, or the scope of the subjoined claims.

Having thus described my invention, I claim:

1. Apparatus for grading multiple choice examination answer sheets using a perforated key sheet, said apparatus comprising: a frame, a plurality of spaced apart photoelectric cells mounted on the frame, a carriage slidably mounted on the frame adjacent the photoelectric cells, a perforated plate on the carriage the perforations in the plate being in substantial registration with the photoelectric cells, illuminating means for directing light through the perforations in the plate; drive means for reciprocating the carriage and the frame relative to each other between loading, scanning and discharge positions; longitudinally disposed guide means on the carriage for guiding the key and answer sheets as they are placed thereon, transversely disposed stop means on the carriage for stopping the key and answer sheets as they are placed thereon, the guide means and the stop means cooperating to position the key and answer sheets on the carriage in superimposed relationship to each other with the perforations in the key sheet opposite the perforations in the perforated plate, means connected to the stop means for moving it from an operative position when the carriage is in its loading position to an inoperative position when the carriage is in its discharge position, a hold-down member adjacent the answer sheet on the carriage; drive means connected to the hold-down member for moving it against the answer sheet when the carriage is in its scanning position and for maintaining it separate from the answer sheet when the carriage is in its discharge and loading positions; discharge means positioned rearwardly of the frame for engaging the answer sheet as the carriage reaches its discharge position and for discharging it therefrom, and computing means in an electric circuit with the photoelectric cells for computing the score of the answer sheet.

2. The apparatus of claim 1 wherein the drive means for reciprocating the carriage and operating the hold-down member comprises a crank rotatably mounted on the frame, and a crank shaft pivoted at one of its ends to the crank and connected to the hold-down member at

the other of its ends, its intermediate portion slidably engaging the carriage.

3. The apparatus of claim 1 wherein the stop means comprises a spring-pressed dog pivotally connected to the carriage and positioned for engagement with a frame member when the carriage is in its discharge position, the frame member moving the dog to its inoperative position against the resiliency of the spring.

4. The apparatus of claim 1 wherein the discharge means comprises a pair of driven friction rollers positioned for gripping the answer sheet when the carriage is in its discharge position.

5. Apparatus for grading multiple choice examination answer sheets using a perforated key sheet, said apparatus comprising: a frame, a plurality of spaced apart photoelectric cells mounted on the frame, a carriage slidably mounted on the frame adjacent the photoelectric cells, a perforated plate on the carriage the perforations in the plate being in substantial registration with the photoelectric cells, illuminating means for directing light through the perforations in the plate; drive means for reciprocating the carriage and the frame relative to each other between loading, scanning and discharge positions; longitudinally disposed guide means on the carriage for guiding the key and answer sheets as they are placed thereon, transversely disposed stop means on the carriage for stopping the key and answer sheets as they are placed thereon, the guide means and the stop means cooperating to position the key and answer sheets on the carriage in superimposed relationship to each other with the perforations in the key sheet opposite the perforations in the perforated plate, means connected to the stop means for moving it from an operative position when the carriage is in its loading position to an inoperative position when the carriage is in its discharge position,

a hold-down member adjacent the answer sheet on the carriage; drive means connected to the hold-down member for moving it against the answer sheet when the carriage is in its scanning position and for maintaining it separate from the answer sheet when the carriage is in its discharge and loading positions; discharge means positioned rearwardly of the frame for engaging the answer sheet as the carriage reaches its discharge position and for discharging it therefrom, computing means in an electric circuit with the photoelectric cells for computing the score of the answer sheet, and printing means in an electric circuit with the computing means and positioned for printing the score on the answer sheet.

6. Apparatus for grading multiple choice examination answer sheets with a perforated key, said apparatus comprising: a frame, a carriage slidably mounted on the frame, drive means for reciprocating the carriage and frame relative to each other between loading, scanning and discharge positions, positioning means on the carriage for positioning the key and answer sheets thereon, a hold-down member adjacent the answer sheet on the carriage, a crank on the frame; a crank shaft pivoted at one of its ends to the crank, connected at the other of its ends to the hold-down member, and slidably engaging the carriage in its intermediate position, whereby to reciprocate the carriage and hold-down member with rotation of the crank; and electronic means on the frame for scanning the answer sheet and scoring the same.

7. The apparatus of claim 6 wherein the positioning means for the key and answer sheets comprises a pair of longitudinal guides positioned one on each side of the carriage and a transversely extending, releasable stop at the rearward portion thereof.
